MOUNTING PLATE FOR FIXTURES EMPLOYING ELONGATED TUBULAR LAMPS

Robert G. Marchisio, Wenham, Mass., assignor to Sylvania Electric Products Inc., Salem, Mass., a corporation of Massachusetts

Application July 1, 1950, Serial No. 171,592

1 Claim. (Cl. 240—51.11)

1

This invention relates to electric lighting fixtures and more particularly to fixtures employing elongated tubular light sources, such as fluorescent lamps.

To the lighting fixture manufacturer, the introduction of each new lamp size presents additional fixture manufacturing problems, one of the more important of which is the stocking of a complete set of fixture components to accommodate the new size lamp. The stocking of different sizes of fixture components for different sizes of lamps not only materially increases the minimum necessary operating inventory but, in the case of some of the longer lamps, such as the 96 inch long, 75 watt fluorescent lamp, for example, assembly operations are quite awkward in a bench-type assembly line system because of the extreme length of the units.

It is, therefore, an object of our invention to provide a device which will permit the use of basic fixture units in fixtures employing lamps of various sizes.

Another object of our invention is to provide a device which will permit the use of basic reflector and light-controlling panel units in fixtures employing lamps of different sizes.

The device of our invention is a mounting plate assembly attached to a unitary chassis intermediate the ends thereof. The mounting plate assembly includes means for supporting the adjacent ends of pairs of reflectors and light-controlling panels.

In the following description and in the accompanying drawing, a specific embodiment of the device of our invention is described and illustrated with reference to a specific type of fluorescent lighting fixture. Other modifications of the device of our invention and their adaptability to fixtures other than the specific one shown and described will be readily apparent to those skilled in the art.

Further objects, advantages and features will be apparent from the following description when read in conjunction with the accompanying drawing in which:

Figure 1 is a plan view of a fluorescent lighting fixture with which the device of our invention may be employed.

Figure 2 is a transverse sectional view of the fluorescent lighting fixture of Figure 1, taken along the line 2—2 thereof, and showing a specific embodiment of our invention.

Figure 3 is a fragmentary top perspective view of the fluorescent lighting fixture of Figure 1.

In the drawing, the fluorescent lighting fix-

2

ture 1 comprises an elongated channel chassis 2 with end plates 3 and 4 attached to the ends thereof, a mounting plate assembly 5 attached to and depending from the chassis 2 transverse thereof and midway between its ends, a pair of reflectors 6 and 7 and a plurality of light-controlling panels 8, 9, 10 and 11. Fluorescent lamps 12 are mounted in holders 13 attached to the inside faces of the end plates 3 and 4. Each of the reflectors 6 and 7 has a plurality of louvers 14 extending transversely thereof and attached thereto.

In the specific modification shown in the drawing, the mounting plate assembly 5 comprises a pair of plates 15, each of which has a louver 16 formed integral therewith, attached to one another, a reflector-supporting member 17 attached to the opposite faces of each of the two plates 15, and a latch 18 pivotally mounted between the offset ends of the louvers 16 at each end thereof. Each of the plates 15 of the mounting plate assembly 5 has a pair of ears 19 formed integral therewith through which the mounting plate assembly 5 is attached to the chassis 2.

As mentioned above, the mounting plate assembly of our invention permits the use of multiple reflector and panels units in assembling fluorescent lighting fixtures. In assembling the instant fixture shown in the drawing, the end plates 3 and 4, with the lamp holders 13 mounted thereon, are attached to the ends of the chassis 2. The mounting plate assembly 5 is then attached to the chassis 2 midway between the ends thereof by securing the ears 19 of the mounting plate assembly 5 to the chassis.

The reflector 6 is then placed in position. One end of the reflector is attached to the end plate 3, by any suitable means. The other end of the reflector has a pair of slots 20 cut therein, through which the reflector supporting member 17, which comprises a pair of resilient metal fingers 21, extends. As this end of the reflector is swung into position, the fingers 21 of the reflector supporting member 17 are depressed to permit the reflector to be moved upwardly a distance sufficient to bring the slots 20 therein in line with the fingers 21. The fingers 21 are then released and snap into the slots 20, thereby securely retaining and supporting this end of the reflector.

The light-controlling panels 8 and 9 are then mounted on the fixture. One end of each of the panels 8 and 9 is attached to or mounted on the end plate 3 in some suitable manner. The other end of each of the panels 8 and 9 is hung

on the hook portion 22 of a bracket 23 mounted on the chassis 2 above and in register with the mounting plate assembly 5.

The reflector 7 and the light-controlling panels 10 and 11 are mounted in the same manner as the reflector 6 and the light-controlling panels 8 and 9 respectively. The latches 18, each of which has a resilient clip 24 attached to the free end thereof, are then swung upwardly into engagement with the adjacent ends of panels 8 and 10 and 9 and 11 respectively. Each of the clips 24 has an offset portion 25 which locks the panels 8, 9, 10 and 11 in the hook portion 22 of the brackets 23.

What I claim is:

A lighting fixture comprising: an elongated channel chassis; end plates attached to the ends of said chassis; at least two reflectors disposed end-to-end beneath said chassis and extending parallel thereto with the ends of said reflectors disposed adjacent to said end plates mounted thereon; a plurality of transverse louvers mounted in each of said reflectors and depending therefrom; a mounting plate attached to said chassis intermediate the ends thereof between 25 the adjacent ends of each of said reflectors; means on opposite faces of said mounting plate for supporting the adjacent ends of each of said reflectors; a transverse louver on said mounting

5 plate and disposed between the adjacent ends of each of said reflectors; at least two light-controlling panels disposed end-to-end, parallel to said chassis along each side thereof and spaced therefrom with the ends of said panels disposed adjacent to said end plates mounted thereon; a bracket mounted on each side of said chassis above and in register with the transverse louver on said mounting plate, the free end of each of said brackets having a hook portion on which the adjacent ends of each of said panels are supported; and a latch pivotally mounted on each end of said transverse louver on said mounting plate and disposed between the adjacent ends of said panels the free end of said latch overlying and frictionally engaging the adjacent ends of said panels at the points at which said panels are supported on said bracket.

ROBERT G. MARCHISIO.
